UNITED STATES PATENT OFFICE.

DICK M. KIRBY, OF AUBURN, NEW YORK.

STEAM-BOILER.

SPECIFICATION forming part of Letters Patent No. 340,327, dated April 20, 1886.

Application filed December 22, 1885. Serial No. 186,413. (No model.)

To all whom it may concern:

Be it known that I, DICK M. KIRBY, a citizen of the United States, residing at Auburn, in the county of Cayuga and State of New 5 York, have invented certain new and useful Improvements in Steam-Boilers, of which the following is a specification, reference being had therein to the accompanying drawings.

This invention has relation to base-burning 10 steam-generators with a central magazine for coal; and the object of the invention is to simplify the construction and to make the fire-box in hollow cast-iron sections, serving as water-spaces, and to suitably connect the same 15 with each other and with a coil, which may be irregular in contour.

Other objects and advantages of my invention will appear in the following description, and the novel features thereof will be particularly pointed out in the claims.

Referring to the drawings, Figure 1 is a central vertical section of a steam-generator constructed in accordance with my invention. Fig. 2 is a perspective of the cap-section, and 25 Fig. 3 of a base or lower section of the fire-box constructed in accordance with my invention.

Like letters indicate like parts in all the figures of the drawings.

To a suitable annular base, A, forming the ash-pit, to which access is had through a door, A', is arranged in any suitable manner the grate B, which may be shaken by means of the lever B'. The base is provided with an inwardly-projecting annular flange, A², upon which, in order to form the fire-box proper of the generator, I mount one or more annular hollow castings or cast sections, C, having radial recesses C' in its upper edge; and between 35 the recesses C' are apertures C², which communicate with the interior of the section, so that when another section is mounted upon the section C similar apertures in said other section register with said apertures C², and 40 thus direct communication between a series of sections is provided.

At the lower end of the section C is arranged a pipe, D, which at that point communicates with the interior of the section, passes 45 upward, and then inwardly through both the inner and outer wall of the section into the

space inclosed by said inner wall, where it communicates with the coil E, arranged within the section or fire-box. The point of connection of the pipe D with the coil E is shown 55 in section at D'. The upper end of the coil is shown in like manner at E', extending through one of the recesses C' of the section C, while another of said recesses C', on the opposite side of the fire-box and near its top, is represented as unoccupied, and forms a passage for 60 the products of combustion.

The cap-section employed with the section or series of sections C (illustrated in Fig. 3) consists, as shown in Fig. 2, of an annular casting, F, which is hollow, as shown in Fig. 1, and is provided with pipes F', communicating with its interior. The pipes F' communicate with similar pipes, G, which are fitted in the outer wall of the lower section, C, and communicate with the interior thereof. A T branch connects the pipes F' and G opposite one of the recesses C' of the lower section, and the coil E is connected to the T-joint. The threads of the connections of the pipes F' and G and the T-joint are such that by turning the vertical portions of said connecting-pipes the cap F is drawn snugly in contact with the section C. There may be as many of said connecting-pipes for the cap and the lower or adjacent section as 80 desired. The central opening, F², in the upper cap is preferably more or less flared, and terminates below with an inwardly-projecting flange, F³, for the purpose of supporting the magazine H, which is cast with a peripheral 85 flange, H', thereon, which comes in contact with and rests upon the annular flange F³. A suitable cover, H², is provided for the magazine. The outlet-pipe I issues from the hollow top casting or cap, F, and a steam and water gage, J, is arranged to communicate with said cap and with the water-space of the lower section. From the top of the cap is supported a depending cylindrical intermediate shell or diaphragm, K, which does not extend 90 completely to the base A², and is to direct the products of combustion downward against the surface of the boiler. An exterior jacket, L, is mounted upon the base and incloses the entire structure heretofore described, and has at 95 its top an uptake or smoke-stack, M, which communicates with its interior. A fusible

plug or other safety appliance, N, may be provided in such manner as to have communication with the interior of the upper chamber or cap, F. A draft-flue, O, is also provided, 5 passing through the several jackets and sections, and communicating with the interior of the lower section, or the fire-box proper. This flue may be formed on or as a part of the lower section, as shown in Fig. 3, or it may be 10 constructed separately therefrom, as desired. The coils may be supported upon brackets P, secured to or formed on the inner wall of the lower section, or they may be supported by any ordinary hanger depending from the upper 15 portion of the apparatus.

This being the construction, the operation is as follows: Coal being fed through the magazine and a supply thereof being maintained therein, the products of combustion pass around 20 and between the coils, and from thence through the passages or recesses C' and into the space between the depending diaphragm K and the outer wall of the section C, and from thence downwardly beneath the lower edge of the 25 diaphragm into the space between the diaphragm and the exterior shell, and thence upwardly to the uptake.

By the construction and operation above described the products of combustion are retained for a comparatively long period of time 30 in contact with the coils, and with the interior and exterior walls of the sectional castings forming the fire-box, so that the heat thereof is communicated to the water within the sections and within the coil. The steam-chamber 35 of the generator is the upper portion of the space within the cap F, so that it will be noticed that the entire coil is below the water-line of the generator.

In constructing a steam-generator as described the cost of manufacture is materially reduced, and the sectional fire-box is protected in a great measure from the high heat to which it is subjected, by reason of being hollow and filled with water, and by the peculiar 45 pipe-connections the circulation of water is maintained therein and in the coil.

Having described my invention and its operation, what I claim is—

50 1. In a steam-generator of the class described, the combination of a fire-box, consisting of an annular hollow cast section having radial recesses at its upper end, with a hollow annular cast cap and a pendent magazine 55 resting on said cap, substantially as described.

2. In a steam-generator of the class described, a fire-box consisting of a hollow annular section having radial recesses, a hollow

cap, and pipe-connections communicating with the interior of the under section and of the 60 cap, substantially as specified.

3. In a steam-generator, the combination of a hollow annular cast section having radial recesses in its upper end, a hollow cast cap, a series of pipes connecting the cap with the 65 annular section, and a coil communicating with the connecting-pipes and with the interior of the lower section, substantially as specified.

4. The combination of a fire-box consisting 70 of an annular hollow section, a cap mounted thereon and communicating therewith by means of exterior pipes, a coil communicating with one of said pipes at its upper end, and with the hollow section at its lower end, 75 and a depending inclosing cylinder or dia-phragm, substantially as specified.

5. The combination of the hollow annular section having radial recesses in its top, the cap mounted thereon and connected therewith, as described, a depending diaphragm, and exterior jacket with an uptake, substantially as specified. 80

6. The combination of the section C, provided with the pipe D, and with the recesses 85 C', the coil E, the cap F, and the connecting-pipes F' G, substantially as shown and described.

7. The combination of the section C, the cap F, the coil E, the pipes F' G, uniting the 90 section C and its cap, and the diaphragm K, resting on the cap, substantially as shown and described.

8. The combination of the cap F, having conical opening F², and the flange F³ at the 95 bottom thereof, and the magazine H, having the flange H', substantially as shown and described.

9. The combination of the base A, the grate B, the section C, having the pipe D, communicating with the lower portion of the interior thereof, the coil E, the cap F, having the flange F³, the magazine H, having the peripheral flange H', pipes F' and G, and the outlet-pipe I, substantially as shown and described. 100

10. The cap F, provided with the pipes F', in combination with the annular fire-box section C, provided with the pipes G, substantially as shown and described. 110

In testimony whereof I affix my signature in presence of two witnesses.

DICK M. KIRBY.
